Jacob Miller,
By atty. A. B. Stoughton.

UNITED STATES PATENT OFFICE.

JACOB MILLER, OF CANTON, OHIO.

IMPROVEMENT IN FANNING-MILLS.

Specification forming part of Letters Patent No. **35,463**, dated June 3, 1862.

To all whom it may concern:

Be it known that I, JACOB MILLER, of Canton, in the county of Stark and State of Ohio, have invented certain new and useful Improvements in the Construction of the Shoe and Riddles of Fanning-Mills; and I do hereby declare the following to be a full, clear, and exact description of the construction and operation of the same, reference being had to the accompanying drawings, making a part of this specification, in which—

Figure 1 represents a longitudinal vertical section through the shoe and its several parts. Fig. 2 represents a vertical transverse section at the line *x x* of Fig. 1.

Similar letters, where they occur in the drawings, denote like parts of the shoe in both figures.

My invention consists in the arrangement of an upper and lower riddle in the shoe with a chute board between them and the second blast-passage and delivering-spout, so that the grain as it passes through the upper riddle will be carried back and fall on the lower riddle to receive a second action of the air from the same blast as it passes to the delivery-spout.

To enable those skilled in the art to make and use my invention, I will proceed to describe the same with reference to the drawings.

A represents a shoe for a fanning-mill, which may be suspended to the frame or sides of the mill by the adjustable straps *B B*, and which may receive its shake motion in any of the usual well-known ways.

C is the main riddle for making the first separation in connection with a blast from a fan-blower. The coarser impurities pass off at the end of the riddle, and, dropping into an inclined trough, *a*, are carried off to the side of the machine. The grain, with such finer impurities as pass through the riddle, and are too heavy to be carried out by the blast under the riddle, drop upon the conducting-board *D*, and are directed onto a second riddle, *E*, at the point *b*, and as the grain and its accompanying impurities pass over this riddle *E* they are

subjected to a second current of air through the passage *F*, which current may come from the same fan-blower that furnishes the blast to the upper riddle, *c*. The air-passage *F* is furnished with a hinged wind-board, *G*, by which the force of the current can be regulated. The cleaned grain, dropping upon the directing-board *H* underneath the lower riddle, is carried into the trough *I*, and, dropping upon an inclined board, *J*, in said trough, may be carried out to the side of the machine. The board *J* may be pivoted at *c*, so that the grain may be carried to either side of the machine that may be desired or most convenient for its reception.

The chaff, dust, and light impurities blown out of the grain as they drop through the first riddle pass out at *d*, and thence into the trough *a*; or the end boards, *e f*, both of which may be raised, removed, or adjusted, may be so set as to allow these impurities to pass off at the end of the machine. The impurities driven off by the second riddle and current of air may pass off at *g*, as well as those which go to the end of said riddle, said riddle extending to the farther side of the trough or slightly beyond it.

This machine may be built and used in connection with thrashing-machines, so as to thresh and clean the grain in one continuous operation, or for cleaning and separating thrashed grain, it being applicable to both operations, whether joint or separate.

Having thus fully described the construction and operation of my shoe for fanning-mills, what I claim therein as new, and desire to secure by Letters Patent, is—

The arrangement of the riddles *C E* and conducting-board *D* with the two wind-passages and the delivery spout or trough *I*, for the purpose of subjecting the grain to a double or second current of air to clean it, substantially as described.

JACOB MILLER.
